DESIGN FOR A POLISH KIT

Benjamin Hill Willingham, Nashville, Tenn.

Application November 6, 1942, Serial No. 108,713

Term of patent 3½ years

To all whom it may concern:

Be it known that I, Benjamin Hill Willingham, a citizen of the United States and a resident of the city of Nashville, county of Davidson, State of Tennessee, have invented a new, original, and ornamental Design for a Polish Kit, of which the following is a specification, reference being had to the accompanying drawing, forming part thereof and in which—

Figure 1 is a plan view of a polish kit showing my new design.

Figure 2 is a side view of the same.

Figure 3 is a left (as seen in Figures 1 and 2) end view of the same; and

Figure 4 is a right (as seen in Figures 1 and 2) end view of the same.

Figure 5 is a sectional view taken along line 5—5 of Figure 2.

I claim:

The ornamental design for a polish kit, substantially as shown.

BENJAMIN HILL WILLINGHAM.
